UNITED STATES PATENT OFFICE.

HENRY C. BEMAN, OF MEADVILLE, PENNSYLVANIA.

DUST-ABSORBING COMPOUND AND PROCESS OF MAKING SAME.

No. 884,558.

Specification of Letters Patent.

Patented April 14, 1908.

Application filed May 27, 1907. Serial No. 375,902.

To all whom it may concern:

Be it known that I, HENRY C. BEMAN, residing at Meadville, in the county of Crawford and State of Pennsylvania, have invented a 5 certain new and useful Dust-Absorbing Compound and Process of Making Same, of which the following is a specification.

It is a well-known fact that in sweeping floors, carpets or rugs where no absorbing 10 compound is used, dust rises from the operation with the result that it is breathed into the lungs by the operator, and a large portion thereof resettles upon the furniture within the room and upon parts swept.

15 My invention therefore has for its object to provide a dust absorbing compound for use, when sweeping, which will effectively absorb the dust and dirt during the sweeping operation at the very point of the broom or 20 brush, and at the same time leave the floor, carpet, or rug, as the case may be, bright and clean, as well as in a sanitary condition.

25 By the use of a small quantity of my compound on the floor or carpet at the place of the beginning of the sweeping operation, and sweeping it along over the surface, all of the dust and dirt is absorbed by the compound, leaving a clean, bright and disinfected, sanitary condition in the room and at the same 30 time driving out any moths, vermin, etc. that may be lurking within the carpet or rug.

35 Another object of my invention is to provide a dust absorbing compound which will result in a great saving of time in cleaning off furniture, goods in stores, etc. after the ordinary manner of sweeping without its use,—goods in stores do not have to be covered up to keep the dust off when my compound is used during the sweeping operation.

40 In its generic nature, my invention comprises a compound consisting of a vehicle or carrier such as granulated wood and the like, containing absorbing oils, a disinfectant and deodorant, an aromatic substance and a 45 coloring matter, so arranged and combined, that when used, it will not soil, stain or injure the carpets, etc. being swept and which will at the same time readily and effectively serve its intended purposes.

50 My compound is composed of the following articles in substantially the following proportions for about a one bushel quantity of wood: Sulfate of iron (copperas) (ferrous sulfate $FeSO_4 + 7H_2O$) 1 pound. Mineral oil, 1

pint. Oil of sassafras, (or other suitable similar substance) 1 ounce. Anilin color matter, 1 ounce.

55 The foregoing ingredients are thoroughly mixed and two gallons of hot water are added, the mixture being thoroughly stirred until the sulfate of iron and anilin crystals are dissolved, after which the material is placed in a vat and the carrier or vehicle added. The anilin crystals which I prefer to use are those containing water of crystallization, 65 such for instance as anilin blue or anilin red.

60 The carrier or vehicle is composed of an intimate mixture of the following ingredients or their equivalents, to wit,— $\frac{3}{4}$ bushels wood pulp. $\frac{1}{4}$ bushel ground corn cobs. 70 1 quart ground peach stones. These ingredients are thoroughly mixed and then added to the aqueous solution hereinbefore referred to. The materials are then thoroughly mixed and stirred together until every particle of the carrier or vehicle has absorbed its share of solution. The material is then dried, either by pressure, centrifugal force, or heat, as may be desired, until the greater part of the water has been evaporated from 80 the compound when a microscopic examination will reveal the fact that every part of the vehicle or carrier contains a crystallized quantity of the matters formerly in solution as well as a slight quantity of the various 85 oily materials. The compound is then ready for use, as hereinbefore stated, and it may be packed in any desired form for commercial distribution.

90 The specific details of manufacture of my compound and the specific steps of the process involved may be varied to suit the requirements of the manufacturer.

95 From the foregoing description, it will be seen that I have provided a very simple and effective compound, embodying a most effective combination of materials which will readily serve their intended purposes.

What I claim is,—

100 1. A process of making dust absorbing compounds, consisting in mixing a disinfectant with dust absorbing oils, water and a carrying medium, drying said carrying medium to evaporate the water and form crystalline substances on the carrying medium, 105 substantially as specified.

105 2. A compound consisting of a carrying medium, dust absorbing oils carried thereby,

together with sulfate of iron, mineral oil, oil of sassafras and color crystals with water of crystallization, substantially as specified.

3. A process consisting in forming an aqueous solution of sulfate of iron, dust absorbing oils and coloring crystals, and then depositing the matters in solution on a carrying medium, substantially as specified.

4. A compound containing granulated wood, sulfate of iron, anilin color crystals, dust absorbing oils and water.

5. A process of forming a dust absorbing compound, consisting in saturating a carrier with an aqueous solution of sulfate of iron, dust absorbing oils and anilin color solution, and then drying the same to evaporate the water, substantially as specified.

6. A compound consisting of a carrying medium composed of wood pulp, ground corn cobs and ground peach stones, combined with dust absorbing oils carried thereby, sul-

fate of iron, mineral oil of sassafras and color crystals with water of crystallization substantially as specified.

7. In a compound of the character stated, 25 a carrier consisting of wood pulp, corn cobs and peach stones in intimate mixture substantially as specified.

8. In a compound of the class described, a carrier consisting of ground wood pulp, 30 ground corn cobs and peach stones in intimate mixture, substantially as specified.

9. A compound consisting of sulfate of iron, oil of sassafras, a coloring matter and a carrier therefor, said carrier consisting of 35 ground wood pulp, ground corn cobs and peach stones in intimate mixture, substantially as specified.

HENRY C. BEMAN.

Witnesses:
